SWITCH MECHANISM

Gilbert Currie, Wilkinsburg, Pa., assignor to Westinghouse Electric & Manufacturing Company, East Pittsburgh, Pa., a corporation of Pennsylvania

Application March 21, 1942, Serial No. 435,617

10 Claims. (Cl. 74—97)

My invention relates, generally, to switch mechanisms, and, more particularly, to quick make and break mechanisms for actuating the contact members of enclosed switches.

An object of my invention, generally stated, is to provide a switch mechanism which shall be simple and efficient in operation and which may be economically manufactured and installed.

A more specific object of my invention is to provide a quick make and break mechanism which shall maintain full pressure on the switch contact members up to the instant of operation.

Another object of my invention is to provide a quick make and break mechanism which is compact in size and positive in operation.

Other objects of my invention will be explained fully hereinafter or will be apparent to those skilled in the art.

In accordance with my invention, a floating cam is so disposed in a pivoted frame which carries the movable contact members of a switch that the frame is actuated about its pivot point with a snap action when the clearance point of the cam passes a fixed pin in the switch structure. The cam is biased against the fixed pin by a spring that is mounted in the pivoted frame and may be actuated by a crank arm extending through the switch housing.

For a fuller understanding of the nature and objects of my invention, reference may be had to the following detailed description taken in conjunction with the accompanying drawing, in which:

Figure 1 is a view, partially in section and partially in front elevation, of a switch mechanism embodying my invention;

Fig. 2 is a view, partially in section and partially in side elevation, of the switch mechanism and housing;

Fig. 3 is a view, partially in section and partially in front elevation, of a portion of the quick make and break mechanism;

Fig. 4 is a sectional view, taken along the line IV—IV of Fig. 3, certain parts being broken away for clearness; and

Figs. 5 and 6 are views, in plan and side elevation, respectively, of the yoke for retaining the biasing spring.

Referring to the drawing, and particularly to Fig. 2, the switch structure shown therein comprises a housing 10 having a removable cover plate 11 at the front and a removable cover plate 12 at the rear thereof for enclosing a contact assembly 13 and an actuating mechanism 14. As shown in Fig. 1, the contact assembly 13 com-

prises a pair of floating contact bars 15 and 16 disposed to alternately bridge stationary contact members 17 and 18, respectively. The bridging contact members 15 and 16 are disposed in a bracket 19 and separated by a spring 21.

In this manner an electrical circuit is established through the contact members 17 when the switch is in the position shown in the drawing and a circuit is established through the contact members 18 when the switch is operated to cause the contact members 16 to bridge the contact members 17. However, it should be understood that the number and arrangement of contact members may be varied in accordance with specific requirements.

As shown, the contact members are substantially enclosed by means of an insulating housing 22, thereby protecting the switch housing 10 against any arcs that may be formed during the interruption of the electrical circuits. The bracket 19 is connected to an insulating member 23 which, in turn, is carried by an arm 24 which is actuated by the switch mechanism in a manner fully described hereinafter.

The actuating mechanism 14 comprises a stationary frame including a pair of spaced plates 25 and 26 separated by pins 27, 28 and 29. The plate 25 is secured to the rear cover plate 12 by a pair of screws 31. A movable frame, comprising plates 32 and 33 spaced apart by pins 34 and 35, is pivotally mounted between the plates 25 and 26 by means of screws 36 and 37 which extend through the plates 25 and 26, respectively. The plate 32 is provided with the upwardly extending arm 24 which carries the insulating member 23 and the contact bracket 19, as hereinbefore described.

A floating cam 38 is disposed in the middle of this assembly and is biased to the position shown by a spring 39. The center of the cam is cut away to provide a space for the spring 39 and the upper end of the spring is retained by a yoke 41 pivotally mounted on the screws 36 and 37 between the plates 32 and 33. The yoke 41 is provided with oppositely disposed notches 42 for receiving the upper end of the cam plate 38. As shown in Fig. 3, the lower end of the spring 39 rests on the cam plate 38, a projection 43 being provided for retaining the spring in position.

As shown in Figs. 2 and 4, the cam plate 38 is disposed between shoulders 44 and 45 provided on the pins 34 and 35, respectively, which together with the notches 42 in the yoke 41 guide the movement of the floating cam 38. As shown

in Fig. 3, the cam 38 is provided with a pair of angularly disposed cam surfaces 46 and 47 for engaging the fixed pin 29 which is preferably provided with a roller 43 for reducing the friction between the cam surfaces and the pin 29. The cam surfaces 46 and 47 intersect at a point 49 which will hereinafter be referred to as the clearance point of the cam.

The cam 38 is provided with a pair of shoulders 51 and 52 which engage the pins 34 and 35, respectively. The cam 38 is also provided with recesses or notches 53 and 54 for alternately receiving the pins 34 and 35, respectively. The plate 32 is provided with shoulders 55 and 56 for alternately engaging the fixed pins 27 and 28.

The cam plate 38 is also provided with a pair of spaced arms 57 and 58 which are alternately engaged by a pin 59 disposed on a crank arm 61 mounted on the inside end of a shaft 62 that extends through the housing 10. A crank arm 63 may be adjustably mounted on the outside end of the shaft 62 by means of a bolt 64 and mounting plates 65 and 66 having serrated surfaces for adjustably positioning the crank arm 63. A roller 67 is mounted at the end of the crank arm 63 by means of a pin 68. It will be understood that the crank arm 63 may be manually operated or, in the event that it is desired to utilize the switch as a limit switch for controlling the operation of a machine or other device, the roller 67 may be disposed for engagement by a cam or other means on the machine which is to be controlled. A roller 69 is preferably provided on the pin 59 for reducing the friction between the pin and the arms 57 and 58 of the cam 38.

If desired, a spring 71 of the torsion type may be disposed around the shaft 62 in such a manner that the crank 63 is returned to a predetermined position when the roller 67 is released, thereby returning the switch mechanism and contact members to the position shown. As shown in Fig. 1, the ends of the spring 71 are spaced apart and disposed to engage a pin 72 fixed in the housing 10 and a pin 73 mounted in the crank arm 61. In this manner tension is applied to the spring 71 when the crank arm 63 is actuated in one direction, thereby causing the arm to be returned to the position shown when released.

Referring to Figs. 1 and 3, it will be seen that if the pin 59 is actuated into engagement with the inside of the arm 58, the cam 38 will be rotated about the pin 34 as a fulcrum and the spring 39 compressed as the cam surface 47 moves over the fixed pin 29. As described in my copending application, Serial No. 376,413, filed January 29, 1941, the recess 53 prevents creepage of the pin 34 along the cam surface 46, thereby retaining full pressure on the switch contact members until the clearance point 49 passes over the center of the pin 29, at which time the spring 39 causes the switch mechanism to snap quickly into its alternate position, wherein the cam surface 46 engages the pin 29 and the shoulder 55 of the plate 32 engages the fixed pin 27. At this time, the pin 35 is forced into the recess 54 in a manner similar to the positioning of the pin 34 in the recess 53, as shown.

Thus, the switch contact members are quickly actuated from the one position to the other and will be retained in that position until pressure is applied on the inside of the arm 57 to operate the switch mechanism in the manner described to return the contact members to the position

shown. It will be seen that the pins 27 and 28 function as stops to limit the travel of the movable plate 32, and, consequently, the travel of the switch contact members.

From the foregoing description it is apparent that I have provided a quick make and break mechanism which is compact in size, positive in operation and which maintains contact pressure on the switch members until the instant of operation of the snapover mechanism. It is also apparent that the mechanism herein described may be mounted inside of an enclosure and operated by means located externally of the enclosure, thereby providing a switch which may be completely enclosed from dirt and other foreign matter.

Since numerous changes may be made in the above described construction and different embodiments of the invention may be made without departing from the spirit and scope thereof, it is intended that all matter contained in the foregoing description or shown in the accompanying drawing shall be interpreted as illustrated and not in a limiting sense.

I claim as my invention:

1. A switch actuating mechanism comprising a support, a frame pivotally mounted on the support and having a switch actuating arm, a plurality of operating pins mounted in the frame, a fixed pin, a floating cam member having two angularly-disposed cam surfaces for alternately engaging the fixed pin, shoulders on the cam member for engaging said operating pins, a spring for biasing the cam surfaces against the fixed pin, and means for operating the cam by overcoming the biasing action of the spring.

2. A switch actuating mechanism comprising a support, a frame pivotally mounted on the support and having a switch actuating arm, a plurality of operating pins mounted in the frame, a fixed pin, a floating cam member having two angularly-disposed cam surfaces for alternately engaging the fixed pin, shoulders on the cam member for engaging said operating pins, a spring disposed in said frame for biasing the cam surfaces against the fixed pin, and means for operating the cam by overcoming the biasing action of the spring.

3. A switch actuating mechanism comprising a support, a frame pivotally mounted on the support and having a switch actuating arm, a plurality of operating pins mounted in the frame, a fixed pin, a floating cam member having two angularly-disposed cam surfaces for alternately engaging the fixed pin, shoulders on the cam member for engaging said operating pins, a spring for biasing the cam surfaces against the fixed pin, a yoke pivotally mounted in said frame for retaining said spring, and means for operating the cam by overcoming the biasing action of the spring.

4. A switch actuating mechanism comprising a support, a frame pivotally mounted on the support and having a switch actuating arm, a plurality of operating pins mounted in the frame, a fixed pin, a floating cam member having two angularly-disposed cam surfaces for alternately engaging the fixed pin, shoulders on the cam member for engaging said operating pins, a spring for biasing the cam surfaces against the fixed pin, and means having a lost-motion connection to the cam member for operating it by overcoming the biasing action of the spring.

5. A switch actuating mechanism comprising a support, a frame pivotally mounted on the

support and having a switch actuating arm, a plurality of operating pins mounted in the frame, a fixed pin, a floating cam member having two angularly-disposed cam surfaces for alternately engaging the fixed pin, shoulders on the cam member for engaging said operating pins, a spring for biasing the cam surfaces against the fixed pin, and rotatable means having a lost-motion connection to the cam member for operating it by overcoming the biasing action of the spring.

6. A switch actuating mechanism comprising a support, a frame pivotally mounted on the support and having a switch actuating arm, a pair of operating pins mounted in the frame, a fixed pin, a floating cam member having two angularly-disposed cam surfaces for alternately engaging the fixed pin, shoulders on the cam member for engaging said operating pins, a spring for biasing the cam surfaces against the fixed pin, a pair of spaced arms on the cam member, and means for alternately engaging said arms to operate the cam by overcoming the biasing action of the spring.

7. A switch actuating mechanism comprising a support, a frame pivotally mounted on the support and having a switch actuating arm, a pair of operating pins mounted in the frame, a fixed pin, a floating cam member having two angularly-disposed cam surfaces for alternately engaging the fixed pin, shoulders on the cam member for engaging said operating pins, said cam member having recesses therein for alternately receiving the operating pins, a spring for biasing the cam surfaces against the fixed pin, and means for operating the cam by overcoming the biasing action of the spring.

8. A switch actuating mechanism comprising a support, a frame pivotally mounted on the support and having a switch actuating arm, a pair of operating pins mounted in the frame, each of said operating pins having a pair of spaced shoulders thereon, a fixed pin, a floating cam member disposed between the shoulders on

the operating pins and having two angularly-disposed cam surfaces for alternately engaging the fixed pin, a shoulder on the cam member for engaging each of said operating pins, a spring disposed in said frame for biasing the cam surfaces against the fixed pin, and means for operating the cam by overcoming the biasing action of the spring.

9. A switch actuating mechanism comprising a support, a frame pivotally mounted on the support and having a switch actuating arm, a pair of operating pins mounted in the frame, each of said operating pins having a pair of spaced shoulders thereon, a fixed pin, a floating cam member disposed between the shoulders on the operating pins and having two angularly-disposed cam surfaces for alternately engaging the fixed pin, a shoulder on the cam member for engaging each of said operating pins, said cam member having recesses therein for alternately receiving the operating pins, a spring for biasing the cam surfaces against the fixed pin, and means for operating the cam by overcoming the biasing action of the spring.

10. A switch actuating mechanism comprising a support, a frame pivotally mounted on the support and having a switch actuating arm, a pair of operating pins mounted in the frame, each of said operating pins having a pair of spaced shoulders thereon, a fixed pin, a floating cam member disposed between the shoulders on the operating pins and having two angularly-disposed cam surfaces for alternately engaging the fixed pin, a shoulder on the cam member for engaging each of said operating pins, said cam member having recesses therein for alternately receiving the operating pins, a spring for biasing the cam surfaces against the fixed pin, a pair of spaced arms on the cam member, and means for alternately engaging said arms to operate the cam by overcoming the biasing action of the spring.

GILBERT CURRIE.
